NONOFFSET SPRAYING DEVICE

William Wilson, New York, N. Y., assignor of one-half to Joseph M. Roschko, Brooklyn, N. Y.

Application December 9, 1941, Serial No. 422,267

11 Claims. (Cl. 91—45)

This invention relates to non-offset spraying devices. It is particularly directed to a spray using dry powder to prevent offsetting and operating entirely by air taken from the air line of the printing press itself.

An object of this invention is to provide a spray, of the character described, to prevent offset in printing, which operates without motor or other electrical equipment, and in which there are no moving parts outside of the valve, and which may be connected to tap air from the usual air supply, which is used in the press to separate sheets, or which may receive compressed air from any suitable source.

A further object of this invention is to provide a highly improved spray device of the character described, which may be used in printing and allied trades to eliminate ink smearing on the sheets technically called "offsetting," said spray device being adapted to spray dry powder to obtain the same results which has heretofore usually been obtained with liquid sprays.

Still a further object of this invention is to provide in a device of the character described, a pair of highly improved nozzles which may be adjustable to spray in any desired directions, one or both of which may be used, the nozzles being furthermore provided with means to catch drip of powder, and being furthermore provided with a removable screen to prevent lumps of powder from being ejected by the spray.

Still a further object of this invention is to provide a compact and durable device of the character described, which shall be relatively inexpensive to manufacture, and practical and efficient to a high degree in use.

Other objects of this invention will in part be obvious and in part hereinafter pointed out.

The invention accordingly consists in the features of construction, combinations of elements, and arrangement of parts which will be exemplified in the construction hereinafter described, and of which the scope of application will be indicated in the following claims.

In the accompanying drawings, in which is shown various possible illustrative embodiments of this invention,

Fig. 1 is a perspective view of a spray device embodying the invention, with parts broken away and in cross-section, and showing the hopper or powder container slightly lifted off its supporting stand;

Fig. 2 is a cross-sectional view taken on line 2—2 of Fig. 1;

Fig. 3 is a cross-sectional view taken on line 3—3 of Fig. 2;

Fig. 4 is a view similar to Fig. 3, but illustrating a modified construction;

5 Fig. 5 is a side elevational view of the device illustrating the position of the device relative to the stack of printed sheets;

Fig. 6 is a rear elevational view of the device relative to said stack;

10 Fig. 7 is a front elevational view of one of the nozzles;

Fig. 8 is a top plan view of one of the nozzles;

Fig. 9 is a cross-sectional view taken on line 9—9 of Fig. 8; and

15 Fig. 10 is a perspective view of one of the screen filters.

Referring now in detail to the drawings, 18 designates a spraying device embodying the invention. The same comprises a stand 11 on which 20 is supported a hopper or other container receptacle 12, containing the powder to be sprayed. The stand 11 comprises a base 13, from which there extends upwardly a vertical tubular support 15. Mounted on tube 15 for vertical adjustment is a member 16 comprising a stem portion 17 received within the tube 15 and adapted to be fixed thereto in various vertically adjusted positions by a set screw 18, or in any other suitable manner.

25 30 Extending upwardly from the stem 17 are three arms 20, inclined upwardly and outwardly. The arms 20 are spaced apart 120 degrees from each other and fixed to their upper ends is a horizontal, flat fixed ring 21. The hopper 12 comprises 35 a substantially conical body portion 24 formed with a clean-out opening 25 at the bottom closed by a threaded plug 26. The body 24 is formed with an annular outwardly extending flange 27 at its upper end contacting the ring 21.

40 45 The top of the container is closed by a closure member 30 having an annular flange 31 at its periphery resting upon the flange 27 and fixed thereto by screws 32 or in any other suitable manner. A gasket 34 of any suitable type may be interposed between the flanges 27 and 31.

The top wall 30 is provided with a filling opening closed by a plug 37. Said top wall 30 is furthermore formed with a central, screw threaded opening 38, and with a pair of screw threaded openings 39 on diametrically opposite sides of the central opening. Screwed within the opening 38 is an air inlet pipe 40 projecting somewhat below the underside of the top wall 30.

Pipe 40 has a constricted opening 42 at its 55 lower end, and is furthermore formed with a

pair of diametrically opposed openings 43, just below the underside of top wall 30 and in alignment with the openings 39. The pipe 40 projects somewhat above the top wall 30, and attached to the upper end thereof, is a T-connection 40a to one branch of which is connected an air hose 45, leading to a valve 46 connected by a hose or pipe 47 to an air supply of a printing press. Pipe 47 may be tapped from the usual compressed air supply of the printing press which supplies air for separating the sheets. Valve 46 is formed with a spring pressed plunger 48 normally retained open by the spring 49 and adapted to close the valve when it is compressed. Pivoted to ears 50 on valve 46 is a lever 51 carrying a roller 52 at one end.

The printing press is provided with an oscillating shaft 53, which oscillates in synchronism with the printing mechanism, and fixed thereto is an arm 54 adapted to engage the roller 52. When the printing press is operating, arm 54 will oscillate to alternately open and close the valve 46 thus supplying compressed air intermittently to pipe 40 and the inside of the hopper 12.

The top of T-connection 40a is closed by a plug 40b formed with an axial screw threaded opening 40c, through which extends screw threaded needle valve 40d to adjust or close opening 42.

Mounted on the top wall 30 are a pair of substantially similar, symmetrically disposed, spray discharge members 60. Each comprises a vertical outlet pipe 61 screwed within one of the screw threaded openings 39 in the top wall 30. Screwed to the upper end of each pipe 61 is an elbow fitting 62, to which there is attached a pipe 63 inclined forwardly, upwardly and outwardly. Each pipe 63 may be provided with a clean-out plug 64, if desired. Attached to the upper end of each pipe 63 is another elbow 65, to which there is connected a flexible tube 66. Attached to each tube 66 is a forwardly extending nozzle member 70. One of the pipes 61 may be provided with a handcock or valve 71, so that if desired, one of the discharge members 60 may be shut off so that either one or both discharge members may be used.

Each nozzle 70 comprises a flattened tubular member 75 fixed to the outer end of the flexible tube 66. Member 75 has top and bottom walls 76 and 77 and increases in width toward the outer end thereof. Said member 75 has an open mouth 78 at its forward end. The top wall 76 thereof however extends beyond the open mouth, forming a lip 79 having a transverse slot 80, for the purpose hereinafter appearing. The lip 79 is wider than the mouth 78, as shown in Fig. 8 of the drawings.

Extending outwardly from the bottom wall 77 are wings 82. Slidably mounted on said wings is a pan 85. The same comprises a bottom wall 86, upwardly extending side walls 87 and inwardly extending, horizontal, aligned flanges 89 contacting the upper surfaces of the wings 82. Extending upwardly from the front end of the bottom wall 86 is a lip or flange 90, extending substantially half the height of member 85. The bottom wall 86 is formed with a pair of spaced openings, through which there extends clamping screws 91 adapted to contact the underside of wings 82.

By loosening the screws 91, the pan 85 may be slidably moved backward or forward relative to the nozzle member 75. As the powder is forced

through the nozzle member, the drippings will be caught within the pan. Furthermore, by longitudinally adjusting the pan relative to the nozzle member, the spray may be prevented from dropping too soon after it leaves the mouth 78.

Mounted on lip 79 is a filter member 100. Filter member 100 comprises a frame 101 slidably extending through the slot 80. The frame 101 comprises folded back portions 102 having outwardly extending flanges 103 at their upper ends. Portions 102 are formed with registering frame openings 105. Inserted between walls 102 is a metal screen member 110.

It will now be understood that the powder must pass through the screen 110, thus preventing lumps from being discharged onto the printing sheets. The pan as well as the filter may be removed for the purpose of cleaning.

The position of the spraying device relative to the stack of printed sheets P is illustrated in Figs. 5 and 6 of the drawings. It will be obvious that the height of the discharge elements may be regulated by moving member 12 up or down on the stand. Furthermore, the flexible tubes 66 permit adjustment of the nozzles in any desired direction. If desired, one of the discharge elements may be shut off by means of valve 71, and in such event, the entire device may be shifted to bring the other discharge nozzle into central location relative to the stack of printed sheets P.

In Fig. 4 there is shown a modified construction, in which the short pipe 40 is substituted by a pipe 40a, to the lower end of which there is attached an axial pipe 40b extending down to a point somewhat above the lower end of the hopper.

The operation of the device will now be described:

The container is filled with powder to a point below the lower end of pipe 40. As arm 54 oscillates compressed air will be intermittently fed to the hopper through pipe 40. The air passing through the lower opening 42 agitates the powder, and the air passing through the openings 43 will direct the powder to the outlet tubes 61. The compressed air will force the powder upwardly through tube 61 and through the discharge nozzles 70 onto each of the printed sheets as it is laid on the stack P.

In the device illustrated in Fig. 4, the agitation is adjacent the apex of the hopper 24.

Although the tank is shown as being mounted on a separate stand, it is understood that the tank in the entire spray device may be mounted directly on any suitable part of the press, eliminating necessity for using the adjustable stand.

The container or receptacle 12 furthermore may have flat sides instead of being conical in shape. It is an advantage, however, that the container decrease in cross-sectional area toward the bottom to allow for easy drainage of powder through the clean-out opening 25, when the plug 26 is removed. Furthermore, with such construction, the amount of air required to agitate the full container is sufficient for a small amount of powder, that is, when there is more powder in the tank or receptacle 12, it is closer to the nozzle 40 and receives a stronger pressure of air to agitate the same. When the height of the powder in the tank decreases, the powder is further away from the nozzle, but there is less powder to be agitated, and therefore, less air pressure is required to agitate the same.

It will be noted that only one of the air discharge elements 70 is provided with a shut off

valve or cock 71. The advantage of leaving one discharge element without a shut off valve is that the operator can see the powder being discharged, thus serving as a reminder to shut off the air supply to the container. If both of the discharge elements had shut off valves, the operator might close both and leave the main air supply to the tank open.

It will be noted that the nozzle 75 increases in cross-sectional area towards its mouth and is fan shaped, thus serving to decrease the force of velocity of the air, and preventing the powder from being discharged at too great a velocity from the nozzle, so that the powder will start dropping almost as soon as it leaves the nozzle. Furthermore, the powder starts spreading within the nozzle and gently falls onto the printed sheets and thus prevents blowing of the powder all over the press or beyond the printed sheets.

It will be noted furthermore that with applicant's construction, the nozzles point toward the press and not away from the press, so that the powder cannot blow into the operator's face.

It is noted that in Fig. 3, there are three openings in nozzle 40, two upper openings and one lower opening, thus providing three agitators for the powder. The lower opening may be shut off. When the lower opening 42 is shut off, the air from openings 43 will have a tendency to pass through the pipes 61 without involving a great deal of powder agitation, and the air blowing through the discharge members serves to clean out the pipes and nozzles. The device is therefore partly self-cleaning. The large refill cap 37 is easily removable to permit a person to see the amount of powder in the container.

It will be noted that the pipes 61 and 63 may be made of any desired size and are replaceable for different sizes of presses.

Although the spray device as illustrated has two discharge devices, any additional amount of discharge devices may be employed. The screens 100 may be of any suitable mesh, and also serves to somewhat retract the discharge of powder, so that the powder does not shoot all over the press. Furthermore, the nozzles 75 may vary in size, if desired.

It will thus be seen that there is provided a device in which the several objects of this invention are achieved, and which is well adapted to meet the conditions of practical use.

As various possible embodiments might be made of the above invention, and as various changes might be made in the embodiments above set forth, it is to be understood that all matter herein set forth or shown in the accompanying drawings is to be interpreted as illustrative and not in a limiting sense.

Having thus described my invention, I claim as new and desire to secure by Letters Patent:

1. In a spray device of the character described, a container adapted to contain powder to be sprayed, an air inlet pipe passing through the top of the container, a pair of pipes fixed to the top of the container, and disposed on opposite sides of the inlet pipe, spraying nozzles connected to said pipes, said inlet pipe extending into the container, and formed with openings directed toward the outlet pipes so as to project air thereto.

2. A device for spraying powder to prevent offset and comprising a container formed with an opening, an air inlet pipe passing through said opening, and projecting into the container, and formed with an opening within said container, and with a pair of spaced openings within said

container, and a pair of outlet pipes extending into said container, said outlet pipes having openings within the container in alignment with said pair of openings in the inlet pipe.

3. A device for spraying powder to prevent offset and comprising a container formed with an opening, an air inlet pipe passing through said opening, and projecting into the container, and formed with an opening within said container,

10 and with a pair of spaced openings within said container, a pair of outlet pipes extending into said container, said outlet pipes having openings within said container in alignment with said pair of openings in the inlet pipe, and nozzles connected to said outlet pipes by flexible pipe connections.

4. A device for spraying powder to prevent offset and comprising a container formed with a central opening, an air inlet pipe passing through

20 said opening, and projecting into the container, and formed with an opening within said container, and with a pair of spaced openings within said container, a pair of outlet pipes on said container having openings in alignment with said pair of openings in the inlet pipe, nozzles connected to said outlet pipes by flexible pipe connections, and a valve on one of said outlet pipes.

5. A device for spraying powder to prevent offset and comprising a container formed with an

30 opening, an air inlet pipe passing through said opening, and projecting into the container, and formed with an opening at its lower end, and with a pair of spaced openings within said container, a pair of outlet pipes on said container having openings in alignment with said pair of openings in the inlet pipe, nozzles connected to said outlet pipes by flexible pipe connections, and a valve on one of said outlet pipes, said outlet pipes being provided with clean-out plugs.

40 6. A device for spraying powder to prevent offset and comprising a container formed with an opening, an air inlet pipe passing through said opening, and projecting into the container, and formed with an opening at its lower end, and with a pair of spaced openings within said container, a pair of outlet pipes on said container having openings in alignment with said pair of openings in the inlet pipe, nozzles connected to said outlet pipes by flexible pipe connections, and a valve on one of said outlet pipes, said outlet pipes being provided with clean-out plugs.

45 50 7. A device for spraying powder to prevent offset and comprising a container formed with an opening, an air inlet pipe passing through said opening, and projecting into the container, and formed with an opening at its lower end, and with a pair of spaced openings within said container, a pair of outlet pipes on said container having openings in alignment with said pair of openings in the inlet pipe, nozzles connected to said outlet pipes by flexible pipe connections, and a valve on one of said outlet pipes, said outlet pipes being provided with clean-out plugs, said container having a plugged opening.

55 60 65 8. In a spray device, a container, an air inlet pipe connected thereto, an outlet pipe on said container, a nozzle on said outlet pipe, a drip pan slidably mounted on said nozzle, means for fixing the drip pan to the nozzle at various adjusted positions, and a screen filter at the mouth of said nozzle.

9. A device for spraying powder to prevent offset and comprising a container formed with an opening, an air inlet pipe passing through said opening, and projecting into the container, and formed with an opening at its lower end, and with a pair of spaced openings within said container, a pair of outlet pipes on said container having openings in alignment with said pair of openings in the inlet pipe, nozzles connected to said outlet pipes by flexible pipe connections, and a valve on one of said outlet pipes, said outlet pipes being provided with clean-out plugs, said container having a plugged opening at its lower end, the top of said container being formed with a plugged opening through which powder may be fed to the container, said nozzle being connected to the outlet pipe by a flexible pipe connection.

10. In a non-offset device, a container for powder, a nozzle projecting into said container, and

having a plurality of openings communicating with the interior of the container, means to supply air to said nozzle, means to shut off one of said openings, a discharge device on said container, and said other openings being directed toward said discharge device so as to project air thereto.

11. In a spray device of the character described, a container adapted to contain powder to be sprayed, an air inlet pipe passing through the top of the container, a pair of pipes fixed to the top of the container, and disposed on opposite sides of the inlet pipe, spraying nozzles connected to said pipes, said inlet pipe extending into the container, and formed with openings directed toward the outlet pipes so as to project air thereto, said inlet pipe being formed with an additional opening within said container, and adjustable means to constrict and close said last opening.

WILLIAM WILSON.
